UNITED STATES PATENT OFFICE.

RICHARD EBLING, OF EAU CLAIRE, WISCONSIN.

DOOR FOR GRAIN CARS.

Application filed May 15, 1922. Serial No. 560,983.

To all whom it may concern:

Be it known that I, RICHARD EBLING, a citizen of the United States, residing at Eau Claire, in the county of Eau Claire and State of Wisconsin, have invented new and useful Improvements in Doors for Grain Cars, of which the following is a specification.

This invention relates to a door for grain cars, and one object is to provide particular means for rendering the door grain tight.

A further object is to provide a door with particular means for throwing the main door toward the side of the car and effecting the required seal after the door has been moved the required distance along the track provided therefor.

A still further object is to provide a grain tight connection by forming a bead on the side of the car around the doorway, and providing a groove on the inner side of the car door, with means for tightening the door and guiding the latter toward the side of the car, and locking it in position with the bead in engagement with the groove on the door.

A still further object is to provide particular locking means and guiding means for the main door.

With the foregoing and other objects in view, the invention consists in the novel construction and arrangement of elements described and claimed, it being understood that modifications may be made within the scope of the claims, without departing from the spirit of the invention.

In the drawings, Figure 1 shows the door in side elevation, a portion of the car wall also being illustrated; Figure 2 is a vertical section on line 2—2 of Figure 1; Figure 3 is a top plan view of the tracks, a portion of the wall being in horizontal section; Figure 4 is a horizontal section on line 4—4 of Figure 1; Figure 5 is a vertical section on line 5—5 of Figure 1; Figure 6 is a detail view, in section, on line 6—6 of Figure 1; Figures 7 and 8 are detail views showing modified securing means for one of the small doors, Figure 7 also showing means for preventing leakage around the edges of one of the small doors.

The side of the car is provided with a doorway 10, and surrounding the doorway is a frame 11, preferably of metal and carrying a bead 12. The portion of the bead at the

left of the doorway, as shown in the drawings, is provided with a bevel 13 on the side nearest the doorway, and the bead on the right is provided with a bevel 14 on the side farthest from the doorway. The inner surface of the door 15 is provided with a groove including an upper portion 17, a lower portion 18, and connecting portions 19 and 20, the two portions last named having beveled walls for cooperation with the beveled portions of the beads located at the left and right of the doorway. These beveled portions facilitate the complete closing of the door for rendering it grain tight. The bevelled portions of the beads are on corresponding sides of the two vertical beads, and the opposite side or edge of each bead constitutes an abrupt wall acting as a stop.

The upper track 22 is mounted on hangers 23, and includes an inner flange 24 deflected inwardly at 25 and secured at 26 to the side of the car. The outer flange 27 beginning at the point 28 is provided with an inwardly curved portion 29, secured at 30 to the side of the car. These inwardly turned and curved portions tend to guide the wheels 28 carried by the hangers 29' and 30', and carry the door inwardly toward the side of the car, so that the groove on the inner surface of the door will come into full engagement with the bead when the door has moved the full length of the track, and distance required to effect closing. The hangers for the door are swivelled, as shown at 31.

A diagonal metallic plate on the door is designated 32, and above and below the latter, in the positions shown are supplementary doorways, designated 33 and 34. These doorways are enclosed by frames 35 for supporting and guiding the doors 36 and 37. Locking devices for the supplementary doors, are designated 38 and 39. The door is provided with a handle 40 for use in moving the door and particular means are provided for guiding the lower portion of the door.

A lower guide 42 includes a downwardly turned portion 43 and an inwardly turned flange 44, with which the hook 45 of each of the elements 46 cooperates. These elements 46 are slidable in grooved brackets 47, and have end portions 48. The object of this arrangement is to prevent the outward movement of the door for a distance of more than two inches.

The locking devices 50 include cam elements 51 for engaging the staple like members 52. Two of such locking devices are provided on each end of the door, with corresponding staples. Each locking device is controlled by a handle 53, and the enlarged portion of the cam is provided with a slot 54 having an offset portion 55. The headed pins 56 pass through the slots, and when the devices are in operative or locking position, with the cams engaging the staples, the offset portions of the slots are in engagement with the corresponding pins. The end portions of the handles are then thrown into engagement with the retaining devices 57. If slight play is provided under the heads of the pins, the handles may be swung outwardly from the edge of the door to a limited extent, to permit of the engagement 15 just referred to. Upon release of the handles from the retaining devices, the engagement between the pins and the offset portions of the slots is no longer effective for retaining the cams in locked position, upon 20 the manipulation of the handles in an obvious manner. The cams are then thrown to position for moving the door laterally or outwardly with reference to the side of the car, thus freeing the grooved portion 25 from the bead surrounding the main doorway. The swivelled hangers for the door permit of the outward and rearward movement of the door, the wheels of the hanger first traveling along the inwardly turned 30 portions of the track, and then along the main portions thereof, permitting the full opening of the door.

In Figure 7, angle bar 58 is positioned along the edge of door 15, adjacent the 40 opening for one of the small doors, and angle bar 59, reversely arranged of the door last named, cooperates with bar 58, in the manner shown, when the small door is closed, thereby producing an effective connection or joint. Obviously, similar provision may be made with reference to the other small door. In each case the opposite edge of the small door, 36 or 37 enters a groove 60, for sealing the joint at this 45 point.

In Figure 8 the locking bolts 64, 65 are pivoted to disk 66, and the latter is rotated by lever 67 adapted to engage retaining de-

vice 68. The bolts enter any suitable securing devices on the door-frame members 55, upon the rotation of the disk by lever 67, and are released by a reverse movement of the lever.

Having thus described the invention, I claim:

1. The combination with the side of a car having a doorway formed therein, of a door for closing said doorway, means for effecting a grain tight connection between the door and the doorway by moving the door inwardly toward the side of the car, a track carried by the side of the car and including inner and outer flanges, one of the flanges turning inwardly at a given point and the other of said flanges turning inwardly at a point spaced therefrom, swivelled door hangers carried by the door and including wheels separately co-operating with the flanges, for guiding the door inwardly towards the side of the car, a stationary guide, and devices carried by the lower edge of the door, slideable along the guide, and slideable with reference to the door, permitting travel of the door and movement outwardly from the side of the car, said devices on the lower edge of the door being each of plate form, and each having its ends turned in opposite directions for respectively engaging the stationary guide and an element fixed with reference to the door, and limiting the outward movement thereof.

2. The combination with the side of a car having a doorway, of a door for closing said doorway, and means for locking the door and for throwing the latter outwardly incident to the unlocking operation, said means including cams, devices carried by the side of the car cooperating with the cams, said cams being formed with slots having off-set portions, pins passing through the slots and into the door for retaining the cams, the pins being adapted to engage the offset portions of the slots, handles for operating the cams, and means for retaining the handles when the pins engage the offset portions, said cams cooperating with the side of the car, for throwing the door outwardly.

In testimony whereof I affix my signature.

RICHARD EBLING.
